UNITED STATES PATENT OFFICE.

WILLIAM F. REMPPIS, OF READING, PENNSYLVANIA.

DESIGN FOR A BICYCLE-FRAME.

46,693.

Specification for Design.

Patented Nov. 24, 1914.

Application filed April 22, 1914. Serial No. 833,813. Term of patent 7 years.

To all whom it may concern:

Be it known that I, WILLIAM F. REMPPIS, a citizen of the United States, residing at Reading, in the county of Berks and State of Pennsylvania, have invented a new, original, and ornamental Design for a Bicycle-Frame, of which the following is a specification, reference being had to the accompanying drawing, forming part thereof.

The figure is a side elevation of a bicycle frame showing my new design.

What I claim is:

The ornamental design for a bicycle frame substantially as shown.

In testimony whereof I affix my signature in presence of two witnesses.

WILLIAM F. REMPPIS.
